ATTORNEYS

UNITED STATES PATENT OFFICE.

HUGO HENRY SOMMER, OF MADISON, WISCONSIN.

ICE-CREAM-OVERRUN TESTER.

Application filed November 12, 1921. Serial No. 514,705.

To all whom it may concern:

Be it known that I, HUGO H. SOMMER, a citizen of the United States, and a resident of Madison, in the county of Dane and State 5 of Wisconsin, have invented a new and useful Improvement in Ice-Cream-OVERRUN Testers, of which the following is a full, clear, and exact description.

My invention relates to improvements in 10 ice cream overrun testers, and it consists in the combinations, constructions and arrangements herein described and claimed:

An object of my invention is to provide 15 a device of the character described in which a direct reading in per cent of overrun of ice cream mix is given.

A further object of my invention is to provide a device of the character described having a moving scale, the reading from 20 which may always be taken from one point on the device.

A further object of my invention is to provide a device of the character described, having a cup for receiving ice cream mix 25 to be tested which is readily accessible, and in which the remaining parts of the device are entirely enclosed.

A further object of my invention is to provide a device which may be adjusted for 30 different sizes of cups and for ice cream mix of different specific gravity.

A further object of my invention is to provide a device which is efficient in operation and which is thoroughly practical 35 commercially.

Other objects and advantages will appear in the following specification, and the novel features of the invention will be particularly pointed out in the appended claims.

40 My invention is illustrated in the accompanying drawings, forming part of this application, in which—

Fig. 1 is a complete section of my device along the line 1—1 of Fig. 2,

45 Fig. 2 is a complete section of my device along the line 2—2 of Fig. 1,

Fig. 3 is a fragmentary view of my device showing the cup holding means,

Fig. 4 is a front elevation of one of the 50 bearing members,

Fig. 5 is a side elevation of one of the bearing members, and

Figure 6 is a fragmentary view of the scale employed in my testing device.

55 In carrying out my invention, I make use of a metal casing 1, which is adapted

to rest upon a base member 2. Thumb screws 3 are provided at the four corners of the base 4 of the casing 1 and provide means of leveling the casing. 60

A substantially rectangular frame 5 is disposed within the casing 1 and secured thereto by screws 6. The sides 7 of the frame 5 have intermediate their length and oppositely disposed to one another, bearing members 8 having agate bearing surfaces 9. Pivottally mounted on the bearing members 8 on the centers 10 is a normally vertical rod 11. The rod 11 has disposed at its lower end a weight 12 which is arranged to 70 be moved up and down upon threads 13 on the rod 11. At the end of the rod 11 above the center 10 is an arcuate scale bearing member 14 having its weight evenly distributed upon the end of the rod 11 by 75 means of the short extended portion 15.

A lever 16 extends outwardly from the rod 11 and is rigidly fixed thereto at an angle of 110° from that portion of the rod 11 supporting the weight 12. The lever 16 80 consists of two legs, each of which bears at its outer ends, bearing centers 17. Pivottally mounted upon bearing centers 17 are a pair of vertical members 18 forming branches of a U-shaped member 19. That the member 19 may always lie in a vertical plane, I have provided adjacent the upper ends thereof two pivotally mounted links 20, which links are disposed in substantial parallel relation with the lever 16 and are 85 pivotally connected at their opposite ends to the sides 7 of the frame 5, as shown at 21. At the lower end of the U-shaped member 19 is a downwardly extending rod 22, which is arranged to pass through an opening 23 of the casing 1. The rod 22 has secured at its lower extremity a stirrup 24. The stirrup 24 is arranged to removably support a cup member 25. 90

A relatively short lever arm 26 is provided and secured in fixed relation to the rod 11 and the lever 16 so that the arm 26 lies in the same plane with the lever 16. The lever arm 26 has pivotally mounted at its outer end thereof a downwardly disposed rod 27 to which a piston 28 is secured. The piston 28 is disposed in a cylinder 29 containing a liquid 30, the upper end of the cylinder having a relatively large opening to permit the angular movement of the 105 rod 27 as the piston is reciprocated. Support for the cylinder 29 is provided by a 110

horizontal plate 31 which is secured to the frame 5, as shown at 32.

Adjacent the lever arm 26 and disposed in parallel relation thereto is a rod 33 which likewise is in fixed relation to the rod 11 and the lever 16. The rod 33 has disposed at its outer end a weight 34, which weight is arranged to move back and forward on the rod by means of threads 35 on the outer portion of the rod 33. The rod 33 is in alignment with the bearing points 19 and 17 so that the centers of gravity on either side of the fulcrum 10 are in a line with the fulcrum 10.

15 The scale bearing member 14 has disposed upon its upper surface a scale 36. The scale 36 is calibrated to read in per cent of overrun in the ice cream mix. Overrun is the increase in the volume of the frozen 20 ice cream mix over the volume of the unfrozen mix expressed as per cent of the unfrozen mix. A hair-line 37 is suspended across from wall to wall of the casing 1 and the reading is taken from the scale at 25 the point directly under the hair-line 37. The casing 1 is provided with an opening 30 having a lens 38 adjacent to the hair-line 37 to assure accurate reading. An electric lamp 39 is provided and extends within the casing 1 for the purpose of illuminating the scale 36.

A door 40 is provided in the casing 1 and furnishes means for reaching the weights 12 and 34 in adjusting the device.

35 From the foregoing description of the various parts of the device, the operation thereof may be readily understood. The device having been set up perfectly level, the cup 25 is placed upon the stirrup 24 and the scale is viewed through the lens 38. If the cup is empty, the reading on the scale should be D or an infinite percentage of overrun. If the reading is not D or infinity per cent overrun, it is adjusted to that reading by means of weight 34. The cup 25 is now removed and filled level full (no cover is used) with the ice cream mix and replaced on the stirrup 24. The reading on the scale 36 should now be zero per cent overrun. If it is not zero, weight 12 is adjusted so that the reading becomes zero.

Now having the device adjusted so that with the empty cup the reading is D or infinity overrun, and with the cup full of the ice cream mix the reading is zero per cent overrun, the device will give the reading of the per cent overrun directly at any time during the freezing process that this particular cup is filled with this particular mix and placed on the stirrup 24.

The piston 28 and the cylinder 29 act in this operation as a dash-pot, that is, a means for preventing undue oscillation of the scale 36 in coming to rest for a reading.

65 To calibrate the device for cups of vari-

ous volumes, the weight 34 must first be adjusted to counter balance the weight of the empty cup. The cup should then be filled with the unfrozen cream and the weight 12 should be adjusted to cause the 70 reading on the scale 36 to be zero per cent.

The D or infinity mark on the scale 36 is so placed that it is under the hair line 37 when the rod 11 is in a vertical position. The zero mark on the scale 36 is so placed 75 that it is under the hair-line when the weight 12 or rod 11 has been deflected through an angle of 40° from the vertical plane. We shall consider the moment of weight 12 in this position as unity (1). 80 The moment of weight 12 necessary for any desired overrun can then be calculated as follows:

$$M \text{ (moment)} \frac{100}{100 + \% \text{ overrun desired}} \quad 85$$

Knowing the moment necessary for a given per cent of overrun we can calculate the necessary deflection and hence can determine the position of the graduation on 90 the scale 36. The deflection necessary is calculated as follows:

$$\tan x = (2M-1) \tan 20^\circ,$$

where angle x is the angle arm 16 makes 95 with the horizontal plane; $-x$ is the angle between the horizontal plane and arm 16 when it is above the horizontal, and $+x$ is the angle between the horizontal plane and the arm 16 when it is below the horizontal 100 plane.

I claim:

1. A device of the character described comprising a cup for holding ice cream, a pivotally mounted lever for supporting said cup, a weight for counter-balancing said cup and lever, a scale associated with said lever bearing legends designating percentages of overrun from zero to infinity per cent in ice cream, and gravity operated means for resisting the movement of said scale by an amount proportional to the displacement of said cup of ice cream, said weight and said gravity operated means adapted for adjustment to various sizes and weights of cups 110 and various specific gravities of said compound, 115

2. A device of the character described comprising a supporting frame, a bifurcated lever pivotally mounted on said frame, a vertical U-shaped member pivotally supported at the outer end of said bifurcated lever, a pair of links parallel with said bifurcated lever and pivotally connected to said U-shaped member and said supporting frame, a cup for holding a compound suspended from the U-shaped member, a scale bearing legends designating percentage of overrun in ice cream carried by said bifurcated lever, and counterweights associated 125 130

with the bifurcated lever for said U-shaped member and cup and for resisting movement of said bifurcated lever respectively.

3. A device of the character described comprising a supporting frame, a bifurcated lever pivotally mounted on said frame, a vertical U-shaped member pivotally supported at the outer end of said bifurcated lever, a pair of links parallel with said bifurcated lever and pivotally connected to said U-shaped member and said supporting frame, a cup for holding ice cream suspended from the U-shaped member, a scale bearing legends designating the percentage of overrun in ice cream carried by said bifurcated lever, and counterweights associated with the bifurcated lever for said U-shaped member and cup and for resisting movement of said bifurcated lever respectively.

4. A device of the character described comprising a supporting frame, a bifurcated lever pivotally mounted on said frame, a vertical U-shaped member pivotally supported at the outer end of said bifurcated lever, a pair of links parallel with said bifurcated lever and pivotally connected to said U-shaped member and said supporting frame, a cup for holding ice cream suspended from the U-shaped member, a scale bearing legends designating the percentage of overrun in ice cream carried by said bifurcated lever, counterweights associated with the bifurcated lever for said U-shaped member and cup and for resisting movement of said bifurcated lever respectively, and a casing for housing all of said device but said cup.

HUGO HENRY SOMMER.
